UNITED STATES PATENT OFFICE

122,295

DESIGN FOR AN OIL BURNER

Frank E. Herr, Lancaster, Pa.

Application June 18, 1940, Serial No. 93,087

Term of patent 14 years

To all whom it may concern:

Be it known that I, Frank E. Herr, a citizen of the United States and a resident of Lancaster, in the county of Lancaster and State of Pennsylvania, have invented the new, original, and ornamental Design for an Oil Burner, of which the following is a specification.

Reference is had to the accompanying drawing, forming part thereof, in which:

Figure 1 is a perspective view of the pump side of an oil burner looking at it from the rear, showing my new design.

Figure 2 is a perspective view also of the pump side of the oil burner, looking at it from the front.

Figure 3 is a rear elevation of the oil burner.

Figure 4 is a perspective view of the motor side of the oil burner.

The dominant features of my design reside in the portions shown in full lines.

I claim:

The ornamental design for an oil burner, as shown and described.

FRANK E. HERR.
